MACHINE FOR MAKING BOX OR CRATE PARTS

Charles S. Berkstresser, Lacochee, Fla.

Application May 9, 1932, Serial No. 610,247

19 Claims.

(Cl. 1—8.1)

This invention relates to box or crate making machinery and more particularly to a machine for making box parts or shooks of the type including side pieces and battens.

5 The general object of the present invention is to provide a novel and improved box part making machine which produces box parts of improved construction and appearance with increased rapidity, greater economy, less labor, and with a minimum number of rejects.

10 The important novel features of the invention may be enumerated as follows:

A. A composite machine for equalizing the side boards, positioning and stapling the battens thereon, and chamfering the edges of the battens.

B. A machine in which the form chain carrying the side pieces moves continuously and at a uniform speed and in which the stapling is done without stopping the movement of the parts.

20 C. A machine in which the side boards are equalized after assembling in the form chain.

D. The provision of means for chamfering the longitudinal edges of all of the battens simultaneously after they have been secured to the side boards.

25 E. The novel constructions of the stapling machines in which the tops are reciprocated by the staple head driving bar operating mechanism.

30 F. The provision of two stapling machines working in opposition and alternately and adjustable in position whereby symmetrical spacing of staples in the side boards is possible in spite of a gap between the boards.

35 G. The driving of staples while the stapling heads are moving at the same speed and in the same direction as the sides and in which clinching of the staples is effected by clinch pins which do not move in the direction of movement of the boards.

40 H. The stamping of a name or trade-mark on a part of each box side for each stroke of one of the stapling machines.

I. The provision for adjustment whereby various sized and shaped parts may be formed on the same machine.

45 Other and further features and objects of the invention will be more apparent to those skilled in the art upon consideration of the accompanying drawings and following specification wherein is disclosed a single exemplary embodiment of the invention particularly in connection with the assembling of the sides of orange crates. It will be understood that this type of crate side is selected merely for convenience in describing the

device and its operation and that the invention is subject to such modifications and changes as fall within the scope of the appended claims without departing from the spirit thereof.

In said drawings:

5 Figure 1 is a side elevation of the box or crate part assembling machine in its entirety;

Figure 2 is a plan view thereof;

Figure 3 is a fragmentary, longitudinal, vertical section taken centrally of the machine;

10 Figure 4 is a transverse section taken on line 4—4 of Figure 2;

Figure 5 is a perspective view of a portion of the side board feed table and main frame;

Figure 6 is a fragmentary, enlarged, transverse, vertical section on line 6—6 of Figure 3;

Figures 7 and 8 are detail views of two positions of the battens and showing the toggle operating to locate the battens on the form chain;

Figure 9 is a fragmentary view of a form chain 20 cleat;

Figure 10 is a fragmentary transverse section on a large scale through a cleat chamfering head;

Figure 11 is a perspective view of a box side 25 as completed on the machine; and

Figure 12 is a vertical sectional view of the marking die and post.

The present invention relates to a machine, which has been disclosed in the present application as constructed for the manufacture of 30 sides for crates for citrus fruit, in which each side comprises two boards, the full length of the crate and slightly less than half the width or depth of the crate, which boards are spaced apart 35 laterally and secured together preferably by three cleats extending transversely of the boards, one at the center of their length and one at each end thereof. The machine is adjustable for the assembly of sides, tops, or bottoms for different 40 size crates or boxes and for different numbers of boards and cleats, but for the sake of convenience it will be described for the manufacture of sides such as shown in Figure 11. These sides with top and bottom when assembled about ends 45 and a center partition, if desired, form a complete crate. The material from which these crates are made is usually rotary cut veneer of approximately $\frac{1}{8}$ of an inch in thickness. The side boards before being assembled in the 50 machine are cut to thickness and width and are cut slightly longer than the desired finished dimension. The cleats are cut to the requisite thickness, width, and length.

Referring now to the drawings and particu- 55

larly to Figures 1 and 2, it will be noted that the machine can be roughly divided into sections, each serving for the performance of one operation. Thus, the section lettered A may be referred to as the feed table for the side boards and includes the moving form chain for positioning and spacing the boards. The part B comprises the equalizer where the boards are carried by the moving form chain between the accurately spaced circular saws to have their ends trimmed squarely and to the proper length to fit between the followers or side guides in the section C, which is the feed table for the battens and includes means for spacing the battens laterally while the form chain includes positioners therefor in respect to the side boards. At D is seen the first stapling machine which puts a pair of staples in each batten for each board. At E is the second stapling machine which likewise places a pair of staples in each batten for each board. At F is a section including only the form chain for clearing the stapled sides from the second stapling machine. At G is the forming or shaping mechanism for chamfering the longitudinal edges of all of the battens simultaneously as the sides are advanced by the form chain and at H is the mechanism for releasing the finished sides from the form chain and advancing them more rapidly than the chain to clear them and deposit them on the inspection table by dropping them down the slides K.

As best seen in Figures 4 and 5, the whole machine is built up about a pair of spaced stapling machines D and E, each having extending from it in a direction opposite to the other machine a pair of inverted channels 10 of appropriate length. These are attached together at appropriate intervals by sections of channel 11 and, where they meet the beds of the machines, are flush therewith and bolted thereto. These side rails form the tables or platforms over which run the spaced form chains 12, and at each end these rails support bearings for shafts 15, 15' each equipped with suitable sprockets 16, as best seen in Figure 3, over which the form chains run. The upper reaches of the chains are straight from sprocket to sprocket, being supported by the rails 10 or as later described, but the lower reaches are depressed at the middle to the point shown by the reference character 18 in Figure 1 to clear certain portions of the stapling machines. From the right-hand end to the stapling machines, these lower reaches run free, but from the stapling machines to the left-hand end (by far the greater distance), their cross members, to be later described, ride on rails 20 supported on cross angles 21 spaced at appropriate intervals along the under flange of the supplementary side channels 22 which are attached to the main frame members and the stapler legs as seen in Figure 1.

These assemblies of frame members are supported at the left-hand end by a set of legs 25, near the center by the bottom stationary frames of the stapling machines, and at the right-hand end by the struts 26 which extend from the right-hand legs of the right-hand machine to the ends of the side frame members.

The shaft 15' carrying the form chain sprockets at the right-hand end of the machine is provided with an outboard mounted drive sprocket 28 driven by chain 29 from the sprocket 30 mounted on a shaft which rotates at a constant uniform speed so that the form chain moves continuously from left to right along the upper

surface of the channel members 10 and between machines D and E for the whole length of the machine, receiving side boards at the left-hand end and carrying them continuously through the machine until they are delivered as completed sides at the right-hand or discharge end. These sprockets 28 and 30 are changeable for changing the form chain rate of travel for different width sides, tops, or bottoms.

The form chains are of conventional construction and are provided at proper and adjustable intervals with links to which may be fastened attachments for spacing the boards and battens to form the box sides. To links of this sort at the same relative spacing on both chains are connected metal cleats 32 which are outside of the chains and space adjacent box sides from each other. These cleats are each provided at the center with an outwardly projecting lug 33 having a hooked forward end 34, the purpose of which is to position the center batten which fits between this hook and the rear of the lug 33 on the preceding cleat. The ends of the cleats 32 are provided with lugs and hooks 35 the same as those at 33 and 34 in the center to serve the same purpose in connection with the end battens as the lugs 33 and hooks 34 serve for the center battens. The cleats 32 are spaced apart along the chains a distance exactly the width of a finished box side. Half-way between them, each side chain is provided with a stud 36 which projects outwardly therefrom and serves the single function of spacing the two boards which form each box side at the proper distance apart and against the cleats 32.

Each side channel 10 has superimposed thereon a narrow inverted channel 40 laterally outside of the chain and of such height that the ends of the cleats 32 rest thereon when the chain rests on the channels 10. Likewise the ends of the side boards rest and travel on these tracks 40. To prevent the boards from moving longitudinally and to properly position them, a guide 41 is secured to each channel 10 outside of the track 40 and has a flaring upper flange 42 to assist in guiding the boards when fed into the chain. These side guide strips 41 are spaced apart a sufficient distance to permit free movement of the roughly sized boards when they are carried along by the form chain. The ends of the channels 40 rest on the beds of machines D and E, and there are removable sections between the machines.

The boards are fed onto the form chain in the section A by operators who stand on either side and insert them in their proper positions, each between a cleat and two side lugs 36 with a cleat in front of one board of a box side and another behind the second one. The boards are carried along by the moving form chain and are drawn beneath the longitudinally disposed hold-down bars 45, four in number. The pair at the center are spaced apart laterally just a sufficient distance to accommodate the width of a batten, and the outer ones are at the proper positions to locate the inner edges of the outer battens. The front ends of these hold-down bars are curved upwardly as at 46 in order that the side boards may readily pass under them. The side boards are made of veneer and are inclined to be warped transversely. These hold-down bars are adjustably supported by bolts 47 from yokes or bridges 48 extending across the machine and secured to the side rails as seen in Figure 1. They tend to flatten the side boards and hold

their ends down against the tracks 40. These hold-down bars continue through the stapling machines and hold the sides down until they have cleared the chamferers.

5 When reaching the position B, the ends of the side boards are engaged by the circular saws 50, shown as mounted on the mandrel 51 extending between bearings 52 carried by blocks on the side rails 10 of the machine. The motor 53 drives the mandrel 51 directly through the flexible coupling 54 and is supported on a frame 55 attached to one side rail and having a separate supporting leg 56. The saws are adjustable along the mandrel or can be mounted on individual motors for the purpose of determining the exact length of the boards which pass through the machine. The saws may be mounted either above or below the form chain and need not necessarily be positioned at the end of the first 10 feed table. They can function equally as well at any subsequent position along the form chain. The motor drives the saws at a high speed, and they cut off the two ends of the side boards to give them an accurate length and insure that the ends are square and at right angles to the axis of the boards. This prevents jamming of the boards in the machine and reduces the number of rejects to a minimum. Trimming the two 15 ends of the boards simultaneously in this manner is referred to as "equalizing."

The side guides 41 are interrupted to accommodate the saws and then continue alongside of the batten feed table C where they are numbered 41', but in this position they are closer 20 together to permit only slight clearance between them and the ends of the equalized boards. These side guides, together with the outer hold-down bars, form channels in which the end battens are placed and which position them adjacent 25 to the ends of the side boards. The center hold-down bars position the battens for the centers of the sides. Both the side guides and the hold down bars are provided with the flaring flanges as previously described in connection with the 30 side guides to assist in the operation of inserting the battens.

In order that the operators who feed the battens may not be required to exercise so much care in their placing, the yoke 48 which supports the hold-down bars just forward of the 35 first stapling machine also supports the pivoted toggles 60 by means of the links 60'. These toggles hang into the paths of the battens and serve to push them into position between the 40 hooked lugs on the cleats of the form chain. This permits the operator to drop the batten into place slightly forward of its final position and with its forward end resting on top of the batten lug which will be eventually in front of 45 it. The toggle will engage this raised end and, because of its considerable weight and inertia, will stop the movement of the batten until its rear end is engaged under the hook on the rear cleat lug when the front end of the batten will drop down behind the lug on the cleat in front of it. The toggle will be pushed forward to 50 swing out of the way until the next cleat comes along if the cleat is not pushed into position by it. These toggles are simple weighted arms pivoted at their tops and hanging into the grooves. The links 60', pivoted to both the yoke 48 and 55 the toggles, permit the toggles to be lifted up in case one of the battens becomes jammed. Their operation will be clear from an examination of Figures 7 and 8.

It is found advantageous to apply a light spring hood 61', as shown in Figure 3, to each hold-down bar 45 just behind the toggles 60 to insure that the battens remain in position until stapled. When three battens in a transverse row are placed in their final position by means of the toggles 60, then one box side is in condition for the application of suitable fastening means to hold the parts thereof together. In the present case the fastening means are staples although it 10 will be realized that nails or other suitable fasteners could be used. However, staples are described because they are at the present time required to comply with the specification of the Freight Container Bureau. 15

As before stated, there are two stapling machines which are identical in construction and operation, and, for the sake of simplicity, the first one reached by the form chain will be described in detail. This machine comprises a 20 suitable base 61 preferably formed integral with the cast legs 62, a pair of which are at each side of the machine and have the feet 63 secured to the floor in any suitable way. This machine base, as previously mentioned, assists in the support of the side rails of the whole assembly. 25

Extending transversely of the machine and journaled in suitable bosses 64 in the right-hand legs, there is a main shaft 65 from which is driven the eccentric shaft 66 of the machine by 30 means of a pinion on the main shaft engaging with the large gear 67 on the eccentric shaft.

The main shafts of the two machines are each equipped with a sprocket 68, which sprockets are connected together by the chain 69 so that the 35 two machines run in unison and at the same speed. The chain 29 which drives the sprocket on the shaft 15' for the form chain passes over the sprocket 30 on the eccentric shaft of the second stapling machine and is driven thereby, 40 which ensures the proper timing between the stapling machines and the form chain.

All of the stapling machine mechanism above the base 61 is carried between the side frames 70 connected together by the tie rod 71 and the 45 beam 72. This upper assembly has, at the bottom of each of the side frames 70, a shoe 73 which runs in ways 74 in the base of the machine, permitting reciprocation of the upper structure of the machine parallel to the axis of 50 movement of the form chain. Upward movement of the upper structure is prevented in any suitable manner such as by using T-heads 75, Figure 6, on the shoes fitting in suitable slots in the ways or in any other well-known manner. 55

The upper structure is provided with a vertically movable driving bar 80 parallel to the floor, extending transversely of the machine and having cross heads 81 operating in the slots 82 in the side frame members 70. Each cross head 60 has extending outwardly therefrom a trunnion 85 upon which is journaled the enlarged upper end 86 of the connecting rod 87 which has secured to its lower end the eccentric strap 88 cooperating with the eccentric 89 on the eccentric 65 shaft 66 of the machine. Rotation of the eccentric shaft causes a full reciprocation of the driving bar for each revolution of the shaft.

Each stapling machine is preferably equipped with three stapling heads 90, 91, 92, the construction of which is wholly conventional and will not be entered into at all in the present description. It is sufficient to state that the stationary portions of these stapling heads are secured to the stationary transverse bar 72 while the movable 75

parts are connected to the driving bar 80 which is operated by the eccentrics. The relative movement of these two parts of each stapling head serves to form staples from suitable wire, cut the wire to provide points on the staples, and drive the staples through the battens and side boards with a portion of the wire projecting beneath the boards.

The stapler heads each form and drive two staples, one in advance of the other and one near each longitudinal edge of the corresponding batten. Thus the three heads on a single stroke of the machine insert six staples. The stapling heads may be constructed similar to the showing in the patent to Lindt, No. 692,882, granted February 11, 1902.

The movable upper structure of each machine is also provided with wire feeding mechanism for the stapler heads indicated at 93 and which is conventional for this type of machine. The wire is fed from the left as seen in Figure 1 and is supplied from suitable reels 96 on the overhead rack 97 supported at 98 from the frame of the machine and suspended as at 99.

The operation of the stapling heads is accomplished by vertical movement of the driver parts thereof, the drivers passing down onto the material of the battens at the finish of the stapling stroke. It will be remembered that the assembled parts for the box sides are moved continuously and uniformly along the conveyor in a line at right angles to the movement of the stapling heads. In order that the stapling can be accomplished, it is essential that the heads also move in the same direction and at the same rate of speed as the boards into which the staples are being driven during the whole time that the staple is engaged both with the wood and with the stapling head. It is for this reason that the stapling machines have their upper structure reciprocable in the direction of movement of the conveyor.

To ensure movement in synchronism and phase with the particular battens into which the staples are to be driven, the upper structures of the machines are reciprocated from the same eccentrics which operate the stapler head driving bar. For this purpose the head of one eccentric strap on each machine is provided with an extension 100 to which is pivoted an adjustable link 101. The opposite end of this link is secured at 102 adjustably in the slot 103 in the lever 104 keyed to shaft 105 held in brackets on the right-hand legs of the machine. The opposite end of the lever 104 is connected by a link 107 to one frame member 70 of the upper structure. The opposite end of shaft 105 carries a short lever linked to frame member 70 so that movement of the whole upper structure in synchronism with the driving bar is ensured. The adjustment of the outer end of the link 101 in the slot in the lever permits changing the length of stroke of the upper structure and to some extent the phase relationship of the movement of that structure and the driving bar. This link is adjustable to insure cooperation of the staple driving heads with the clinch pins to be later described. This adjustment of the link 101 in the slot 103 also permits changing the rate of travel of the driving assembly heads in the direction of movement of the form chain so that the rate of speed of the two is substantially identical during the staple driving operations. The speed of movement of the form chain is adjustable as previously mentioned and permits vary-

ing the spacing between sets of staples driven in any particular box side. When the speed of the chain is increased to increase the spacing between staples then the rate of movement of the stapler heads in the direction of chain movement must also be increased so that there is no relative movement between the stapler heads and the side parts during the actual staple driving.

The adjustable length of the link 101 permits some change in phase relationship of the two staple driving machines without changing the relative rate of travel of the heads thereof and the form chain.

As clearly shown in Figure 12, there is attached to the movable driving bar 80 of one of the stapling machines a post 108 guided in an aperture in a member 108' secured to the lower fixed bar 72 of the machine. This bar carries at its bottom a steel die 109 positioned to engage and impress a name, trade-mark, or the like into one of the cleats, preferably the center one at the same time that staples are driven. One impression is made for each stroke of this machine and is made without the use of ink, merely compressing the wood fibers.

The first stapling machine is permanently attached to the floor and has secured to the legs on each side a bar 110 to which the second stapling machine is adjustably secured. This permits the second machine to be moved longitudinally of the conveyor, necessitating only lengthening or shortening the connecting chain between the main shafts of the two machines and supplying channels 40 and 112 (to be later described) of the proper length, and permits an adjustment of the spacing between staples driven by the two machines. In operation the first machine is adjusted to drive staples first at the forward ends of the battens. On its second stroke it drives a set of staples in the battens near the forward edge of the second board. The second machine on its first stroke on the same box side drives the second set of staples from the forward ends of the battens and on its second stroke drives the last set of staples near the rear ends of the battens. The machines thus put in alternate sets of staples in each side.

However, both machines do not operate on the same side at the same time but are engaged in stapling two different sides. The spacing between the two sets of staples in the batten for each board is different than the spacing between adjacent sets of staples on the two sides of the space between the boards of one side, and for this reason the adjustment of the machines is provided so that four sets of staples can be driven with the desired spacing between the sets in the boards and another desired spacing between the staples straddling the space between boards. Furthermore, this adjustment permits operation on different sizes of boards and sides for making other types of crates. Box or crate parts can also be made with different numbers of boards or slats and with varying numbers of staples and spacing thereof in each which might in some cases cause one machine to apply more staples in one part than the other machine and vice versa for the next part.

In order to provide smooth operation, the machines are set in opposition, i. e., one machine has its driving bar moving upwardly while the other is moving downwardly, and one machine is traveling forward while the other is moving backward. This reduces vibration to a minimum and permits

a material increase in the speed of operation of the whole machine.

Referring now to Figures 3 and 4, it will be seen that the boards not only rest on the side rails 40, but there is a central rail formed by the inverted channel 112 which supports the central portions of the side boards. This rail as well as the rails 40 are in parts and abut the clinch blocks 113 mounted on the stapling machine beds. The tops of the rails and blocks are flush. The blocks are drilled directly beneath the stapling heads in their lowest position, with circular holes 114 considerably larger than the area covered by the staple points, and, in these openings, operate the clinch pins 115, two for each block, since two staples are driven by each stapler head.

The clinch pins are secured together in pairs by blocks (not shown) and rest on brackets 116 secured to a transverse bar 116 operating in suitable vertical ways in the base of the machine and are connected by links 117 to intermediate portions of the levers 118 pivoted at 119 on a rod extending clear across the machine and secured 25 in the legs thereof. The free ends of the levers are provided with cam follower rollers 120 which bear on the peripheries of the discs 121 mounted on the eccentric shaft 66 and each truly circular except for the lobe 122 of short arcuate extent 30 which, when striking the follower roller at high speed, gives the clinch pins a quick upward thrust and clinches the staples so rapidly against the stapler heads which are now bearing on the upper surfaces of the battens that the continuous 35 movement of the boards is immaterial. Two clincher operating cams are provided, spaced sufficiently widely apart so that the return reach of the form chain passes between the clincher bar thrust links 117, as clearly seen in Figure 4.

40 Power is applied to drive the stapler mechanisms as well as the form chain from the electric motor 125 carried by the platform 126 supported on legs 127 from the floor. The motor is equipped with appropriate starting mechanism 128 which 45 controls all other motors and drives the clutch wheel 129 through a series of V-belts 130. This wheel houses a conventional clutch controlled by one or more long foot levers 132 extending to the feed tables so that the operators may stop and 50 start the machine without leaving the position for feeding material to the machine. The driven member of the clutch is mounted directly on an extension of the main shaft of the first stapler machine.

55 The completely stapled sides are carried from the machines, still under pressure by the hold-down bars, to the station G where the edges of the battens are chamfered. At this station there is a transverse mandrel 135 carried in suitable 60 bearings 136 supported from the side rails of the machine. This mandrel is driven by a motor 138 supported in the same manner as is the motor 53 for the equalizing saws. On this mandrel are mounted cutter heads 140, one for each batten. 65 These constitute circular discs slotted to receive cutters 141 as seen in Figure 10, the cutting edges of which are profiled as seen in that figure to chamfer or remove the corners of the longitudinal edges of the battens and to clear the cleat hooks 33 and 35. These cutters with their mandrel and heads really comprise three shapers which are driven at high speed by their motor and produce a fine smooth chamfer on the battens, which 70 improves their appearance materially and reduces

the possibility of injury by splinters when handling the boxes or crates.

Both the equalizer saws and the shaper heads for chamfering are provided with suitable dust hoods 150, shown only in Figure 1 since in the other figures they would hide the structures which they house. These hoods are connected by suitable ducts 152 to appropriate suction fans (not shown) or like devices and serve for removing chips and sawdust from the cutters to prevent 10 it from clogging the machine. To protect the inspector from chips which might be thrown by the chamferer heads, there is a shield 154 secured to the yoke 48 at the far end of the machine and extending substantially down to the surfaces of 15 the boards passing along on the form chain.

Upon leaving the station where the chamfering is performed, the finished sides approach the end of the form chain. Mounted on the shaft 15 which carries the sprockets 16 for this 20 end of the form chain is a pair of circular discs 156 somewhat larger in diameter than the sprockets and one arranged outside of each sprocket in a position to be beneath the end batten. The purpose of these discs is to engage beneath each 25 finished side as it approaches and, because of their superior diameters, to lift the forward edge of the side to release it from engagement with the rear of the lugs on the cleat in front of it. When the side reaches substantially the tops of the discs 30 156, it is pushed, by the lugs behind it, beneath the idler rollers 157 mounted on the shaft 158 loosely journaled in the arms 159 pivoted at 160 to the ends of the side guides 41. The weight of this assembly, including the idlers 157, causes 35 sufficient friction between the discs 156 and the material of the finished side to permit these discs to now cause the forward movement of the side, and since the discs are greater in diameter than the sprockets, the side is advanced more rapidly 40 than the chain and hence is released from beneath the hooks on the cleat lugs behind it. In this manner the sides are successively freed from the chain, advanced more rapidly than the chain, and delivered to the chute 170 which deposits 45 them on an inspection table, not shown, for inspection prior to bundling and shipping.

It will be seen that the whole machine is extremely simple in construction and is capable of operating as rapidly as the boards and battens 50 can be supplied to it. It has been operated at the rate of thirty thousand sides per day of ten hours, which sides are much superior to those produced by machines in which the parts are advanced in steps to permit the operation of the 55 stapling devices while the boards are stationary. The steady movement of the chain does not displace the boards and battens relative to each other, and it insures a more uniform product, due to the equalizing having been done on the 60 chain form in which the stock is held, and one in which the number of rejected parts is reduced to a minimum. By having several operations performed on the same machine, there is a great saving in the handling of the parts, in the number 65 of operators required, and in the space demands for machinery for finishing crate sides.

Having thus described the invention, what is claimed as new and desired to be secured by Letters Patent is:

1. In a machine for forming box or crate parts, each from one or more boards and battens, in combination, conveyor mechanism having means to receive and space the boards, equalizing saws in the path of the ends of said boards while mov- 75

ing on said conveyor to reduce the boards to a uniform length, means to maintain battens in relative position to a board, means for applying fasteners to secure the battens to the boards while on the conveyor, and chamfering means to bevel or round the edges of said battens while being moved from the fastening position by said conveyor.

2. In a machine for forming box or crate parts from boards and battens, in combination, a steadily moving conveyor mechanism to receive and hold a succession of boards with their major axes transverse to their direction of movement, means including said conveyor to receive and position battens each with its axis parallel to the direction of movement of the conveyor and with the battens properly allotted to the boards, a pair of fastener driving machines each adapted to function to apply alternate rows of fasteners for securing the battens on the boards, means to drive said machines in synchronism, and means constructed for adjustment to change the phase relationship of the machines to obtain the proper fastener spacing.

25 3. In a machine for forming box or crate sides from boards and battens, in combination, a conveyor mechanism to receive and hold the parts of a plurality of sides, means to move said conveyor steadily and at uniform speed, a pair of fastener 30 driving devices longitudinally spaced along the path of said conveyor, means to move the driving parts thereof each in unison with the conveyor during the driving stroke thereof and to actuate said devices alternately, said fastener driving devices being adjustable relative to each other to permit of different fastener spacing as desired.

4. In a machine for forming box sides from boards and battens, in combination, a conveyor mechanism to receive and hold the assembled 40 parts of a plurality of sides spaced therealong, means to move said conveyor at a uniform speed, a pair of fastener driving assemblies spaced along the path of the said conveyor, and means to move the fastener driving parts of the assemblies in 45 the same direction and at the same speed as the side parts during the actual driving operation, means to permit changing the relative positions of said assemblies and means to permit changing the ratio of conveyor speed to stroke rate whereby 50 fastener pattern control is had for sides with different numbers of boards.

5. In a machine for forming box sides from boards and battens, in combination, a conveyor mechanism to receive and hold the assembled 55 parts of a plurality of sides spaced therealong, means to move said conveyor at a uniform speed, a pair of fastener driving assemblies spaced along the path of the said conveyor, means to move the fastener driving parts of the assemblies in the 60 same direction and at the same speed as the side parts during the actual driving operation, and means to permit of independent adjustment of said assemblies along said path to position them so that one completes an operation of at least 65 one driving stroke on one side while the other completes an operatin on another side.

6. In a machine for forming box sides from boards and battens, in combination, a conveyor mechanism to receive and hold the assembled 70 parts of a plurality of sides spaced therealong, means to move said conveyor at a uniform speed, a staple driving mechanism having a stationary portion beneath said conveyor and a portion above said conveyor reciprocal parallel to the conveyor, staple driving heads on said reciprocal

portion, means on the stationary portion to move said heads for staple driving, said means being operatively associated with the reciprocal portion to drive it in unison with the movement of the heads for staple driving, whereby staples can be driven while the side boards are in motion and means to permit adjustment of the staple driving mechanism bodily longitudinally of the conveyor. 5

7. In a box side assembly machine, in combination, a conveyor mechanism including a form 10 chain having spacing means to receive side boards with their major axes transverse to its axis of movement, means on said form chain to position battens with their major axes longitudinally of the chain and in definite relationship to the 15 boards, hold-down bars adapted to engage the upper surfaces of the boards, said bars being so spaced as to form lateral positioning and guide means for said battens, and mechanism for performing successive operations on said boards and 20 battens while held by said means and hold-down bars.

8. In a box side assembly machine, in combination, a conveyor mechanism including a form 25 chain having spacing means to receive side boards transverse to its axis of movement, hold-down bars spaced above a portion of said chain and adapted to engage the upper surfaces of 30 said boards when carried thereunder by the chain, equalizing saws in the path of the ends 35 of said boards when under the hold-down bars, means including parts of the form chain and the hold-down bars to position battens above and in predetermined relation to sets of boards on the chain, and staple driving mechanism along the 40 path of said conveyor and adapted to secure the battens to the boards while the conveyor is in motion.

9. In a box side assembly machine, in combination, a conveyor mechanism including a form 45 chain having spacing means to receive side boards with their major axes transverse to its axis of movement, hold-down bars spaced above a portion of said chain and adapted to engage the upper surfaces of said boards when carried 50 thereunder by the chain, equalizing saws in the path of the ends of said boards when under the hold-down bars, means including parts of the form chain and the hold-down bars to position battens in predetermined relation to boards on 55 the chain, staple driving mechanism along the path of said conveyor and adapted to secure the battens to the boards while the conveyor is in motion, and mechanism beyond said stapler adapted to simultaneously chamfer the edges of all of the battens on a side while the boards are held down by the hold-down bars.

10. The method of making box sides comprising positioning boards in proper relationship, imparting steady movement to said boards in 60 a direction parallel to the plane of their upper surface and at right angles to their axes, simultaneously trimming both ends of each board, applying battens above said boards, fastening the battens to the boards while both are in motion, and then chamfering the edges of the battens without stopping the motion of the boards. 65

11. In a machine for forming box sides, in combination, staple driving means adapted to drive staples through battens and boards while 70 in motion, a conveyor including a form chain for holding boards in the position they will take in a finished box side and hold-down bars adapted to position battens laterally of the boards and conveyor, means to drive said chain at a 75

uniform speed, equalizing means for said boards positioned to engage them while moving with the form chain, and chamfering heads disposed laterally of the conveyor path in accordance with 5 the batten positions as determined by the hold-down bars to chamfer the batten edges while the battens move on the chain.

12. A staple driving machine for use with a board conveyor driven at uniform speed including, in combination, a stationary base, a shaft journaled therein, means to drive said shaft, an upper structure slidably mounted on said base for reciprocation parallel to the axis of the conveyor, a staple driving head having a 10 portion rigid with said upper structure, a driving bar reciprocably mounted in said upper structure and having a part of said staple driving head secured thereto, an eccentric on said shaft, and means for imparting motion from said eccentric to both the upper structure and to the driving bar whereby motion of the upper structure is positively synchronized with that of the 15 staple driving head.

13. In a machine for forming box or crate parts from boards and battens, in combination, a conveyor chain, means on said chain to receive and hold a succession of boards with their major axes disposed transversely to the direction of movement of the chain, hold down bars adapted to engage the upper surfaces of the boards, said bars being so spaced as to form lateral positioning and guide means for battens, means on the said chain to engage the rear end of each batten and position it in definite relation to a 20 board and means between the guide bars to finally position the battens against their end engaging chain parts whereby the operation of hand feeding the battens can comprise merely throwing them between the guide bars.

14. In a device for positioning battens on a moving form chain having spaced driving lugs operating between longitudinal guide bars, in combination, a weight and means pivoting said weight at its upper end and positioning its lower 25 end between said bars to just clear the lugs.

15. In a machine for forming box or crate parts, in combination, a travelling form chain to receive and loosely hold boards and superposed battens, means to insert fastening means through 30 the battens and boards to secure them together and means to then chamfer the batten edges while still on the form chain.

16. In a machine for forming box sides from boards and battens, in combination, a conveyor mechanism to receive and hold the assembled parts of a plurality of sides spaced therealong, means to move said conveyor at a substantially uniform speed, independently operable fastener driving assemblies longitudinally spaced along 35

the path of said conveyor, means to so reciprocate the fastener driving parts of the assemblies that during the driving strokes they are moving at substantially the same speed and in the same direction as the side parts, and means to permit changing the ratio of conveyor speed to fastener stroke rate whereby control is had of the spacing of fasteners in the side parts. 5

17. In a machine for forming box sides from boards and battens, in combination, a conveyor 10 mechanism to receive and hold the assembled parts of a plurality of sides spaced therealong, means to move said conveyor at a substantially uniform speed, independently operable fastener driving assemblies longitudinally spaced along the path 15 of said conveyor, means to so reciprocate the fastener driving parts of the assemblies that during the driving strokes they are moving at substantially the same speed and in the same direction as the side parts, means to permit changing 20 the ratio of conveyor speed to fastener stroke rate, and means to permit adjusting the rate of travel of the fastener driving parts in the direction of conveyor travel to compensate for changes 25 in conveyor speed.

18. In a machine for forming box sides from boards and battens, in combination, a conveyor mechanism to receive and hold the assembled parts of a plurality of sides spaced therealong, means to move said conveyor at a substantially 30 uniform speed, independently operable fastener driving assemblies longitudinally spaced along the path of said conveyor, means to so reciprocate the fastener driving parts of the assemblies that during the driving strokes they are moving 35 at substantially the same speed and in the same direction as the side parts, means to permit changing the ratio of conveyor speed to fastener stroke rate, and means to permit adjusting the range of travel of the fastener driving parts in 40 the direction of travel of the conveyor to compensate for changes in conveyor speed.

19. In a machine for forming box sides from boards and battens, in combination, a conveyor mechanism to receive and hold the assembled 45 parts of a plurality of sides spaced therealong, means to move said conveyor at a substantially uniform speed, fastener driving assemblies spaced along the path of said conveyor, means to so reciprocate the fastener driving parts of 50 the assemblies that during the driving strokes they are moving at substantially the same speed and in the same direction as the side parts, means to operate said fastener assemblies so that their driving strokes are in uniform staggered relation 55 to reduce vibration, and means permitting the relative spacing of said assemblies to be changed while retaining said relation.

CHARLES S. BERKSTRESSER.
